UNITED STATES PATENT OFFICE.

JOSEPH F. WALL, OF WESTFIELD, NEW JERSEY.

WINDOW SCREEN.

Application filed November 7, 1921. Serial No. 513,424. Renewed March 8, 1923.

To all whom it may concern:

Be it known that I, JOSEPH F. WALL, a citizen of the United States, residing at Westfield, in the county of Union and State of New Jersey, have invented certain new and useful Improvements in Window Screens; and I do declare the following to be a full, clear, and exact description of the invention, such as will enable others skilled in the art to which it appertains to make and use the same.

My invention relates to improvements in window screens of the type employing a single unbroken sheet of woven wire connected at its edges with a frame which is adjustable both vertically and horizontally, the strands of the wire being positioned diagonally of the frame sides and being free to move on each other as the frame is extended in either direction. I am aware that screens of this type have been heretofore devised, employing four right angular frame sections whose arms are telescopically engaged with each other, but it is the principal aim of the present invention to provide an improved structure which may be more easily and less expensively manufactured, novel provision being made whereby instead of necessarily telescoping the sections of the frame, they may merely overlap each other in a sliding manner.

A still further object of the invention is to provide improved means for insuring the proper movement of the several side bar sections, in parallelism with each other.

With the foregoing in view, the invention resides in the novel subject matter herein-after described and claimed, the descriptive matter being supplemented by the accompanying drawings.

Figure 1 is a front elevation of a window screen constructed in accordance with my invention.

Figure 2 is an edge view.

Figures 3, 4 and 5 are detail horizontal sectional views as indicated by the lines 3—3, 4—4 and 5—5 of Fig. 1.

Figure 6 is a perspective view of the sheet of woven wire, showing the manner of bending its edges for sliding engagement with the frame.

Figure 7 is a fragmentary edge view part-

ly in section showing a modified form of construction.

Figure 8 is a detail horizontal sectional view as indicated by line 8—8 of Fig. 7.

In the drawings above briefly described, the numeral 1 designates a rectangular sheet of woven screen wire, whose edges are slit transversely at intermediate points, the half of each edge at one side of the slit being bent in one direction, while the half at the other side of said slit is bent in the opposite direction, thus forming a pair of oppositely extending flanges 2 on each edge of the sheet, which flanges are preferably of L-shape in transverse section. As shown clearly in Figs. 1 and 6, the several strands of the woven wire are positioned diagonally of the sheet and it is to be clearly understood that these strands are absolutely free of connection with each other so that they may relatively move when the retaining frame is extended either vertically or horizontally.

The numeral 3 designates in a general way the four side bars of a frame for the sheet 1, said bars being rigidly secured together at their corners by appropriate metal brackets 4. Each of the bars 3 is preferably although not necessarily constructed of wood and is formed of two overlapping sections 5 which contact slidably with opposite sides of the sheet 1, said sections being provided in their inner faces with longitudinal channels 6 which slidably receive the hooked ends of the strands forming the flanges 2. Each side bar section 5 is by preference formed of two strips of wood secured together by brads or the like 7 as shown clearly in the transverse sectional view.

While any preferred means may be employed for slidably connecting the overlapping sections 5 of each side bar 3, I have shown angular metal slides 8 for this purpose, said slides being secured to one bar section and bent around the other as shown.

By using the construction shown, the frame and the sheet of wire may be adjusted to adapt the screen to windows of different sizes and shapes. By pulling upwardly on the top side bar and downwardly on the bottom bar, the screen is vertically extended, during which operation, the sections of said top and bottom bars slide in-

wardly upon each other while the sections of the vertical bars slide outwardly upon each other as will be readily understood by comparing the full and dotted line positions of Fig. 1. To assist in operating the frame in this or a similar manner and to insure that the opposed side bars thereof shall maintain the proper parallel relation with each other, I preferably associate some form of spring means with said side bars. In the form of construction shown in Figs. 1 to 5, an endless hoop 9 is placed under tension within the frame of the screen, said hoop being of approximately circular form before it is inserted into the frame, although it will assume the flat-sided condition illustrated in Fig. 1 when applied to said frame. It will be seen that the hoop bears against the inner portions of all four side bars of the frame and thus exerts equal outward stress thereon. This will obtain the required result in a simple and inexpensive manner. The sheet of screen wire 1 prevents movement of the hoop in one direction from the frame and any suitable means such as the pins 10 may be employed to hold it against movement in the other direction.

In Figs. 7 and 8, I have shown a modified form of spring means which may be associated with the sections 5 of each side bar of the frame. In these views, the inner adjacent sides of the sections are longitudinally grooved as at 11 and a coil spring 12 is positioned in said grooves, being connected at one end to one section and at its other end to the other section. The action of these spring is the same as the spring hoop 9.

From the foregoing, taken in connection with the accompanying drawings, it will be seen that I have provided a very simple and inexpensive, yet a highly efficient and desirable window screen which, while employing a single unbroken sheet of wire will be readily adjustable to windows of different sizes and shapes. Since excellent results may be obtained from the details disclosed, they may be followed if desired. I wish it understood however that the present disclosure is for illustrative purposes only

and that within the scope of the invention as claimed numerous minor changes may be made.

I claim:

1. A window screen comprising a sheet of woven wire having its edges bent to provide each edge with oppositely extending lateral flanges, and a frame for said sheet having side bars formed of overlapped slideable sections at opposite sides of the sheet and having longitudinal channels slidably receiving said flanges; the strands of said woven wire being diagonal with respect to the frame and being free to move on each other. 65

2. A window screen comprising a sheet of woven wire having its edges slit between their ends, one half of each edge being bent laterally in one direction while the other half is similarly bent in the other direction, 70 forming oppositely extending flanges, and a frame for said sheet having side bars formed of overlapped slideable sections at opposite sides of the sheet and having longitudinal channels slidably receiving said flanges; the strands of said woven wire being diagonal with respect to the frame and being free to move on each other. 75

3. A window screen comprising a sheet of woven wire whose strands extend diagonally with respect to its edges and are free to move on each other, a frame with which the edges of the sheet are slidably connected, the side bars of said frame being formed of relatively slideable sections, and spring means acting on said sections to insure uniform sliding of opposed side bars. 80 85

4. A window screen comprising a sheet of woven wire whose strands extend diagonally with respect to its edges and are free to move on each other, a frame with which the edges of the sheet are slidably connected, the side bars of said frame being formed of relatively slideable sections, and a spring metal hoop bearing under tension against all sides of said frame for the purpose set forth. 90 95

In testimony whereof I have hereunto set my hand.

JOSEPH F. WALL.
